ATTORNEYS.

UNITED STATES PATENT OFFICE.

MARTEN MANFRED, OF SANTA BARBARA, CALIFORNIA.

SUCTION-WASHER.

1,391,265.

Specification of Letters Patent. Patented Sept. 20, 1921.

Application filed March 24, 1921. Serial No. 455,195.

To all whom it may concern:

Be it known that I, MARTEN MANFRED, a citizen of the United States, residing at Santa Barbara, in the county of Santa Barbara and State of California, have invented new and useful Improvements in Suction Washers, of which the following is a specification.

My invention relates generally to laundry drying appliances, and more particularly, to a clothes washing device in the nature of a dolly or pounder, and the principal object of my invention is to provide a relatively simple and efficient device that is adapted to be manipulated by hand, in a tub or similar container, for forcing water through the articles that are being laundered, and, further, to provide a device having an automatically operating valve that will close an opening through the body of the device on the upward movement thereof, thereby causing said device to exert suction on the articles being laundered during such upward movement, and said valve, on the downward movement of the device, moving to a position where it will act as a deflector for water that passes through the opening in the body of the device and causing said water to be forced or thrown radially outward with considerable pressure, and consequently acting to very quickly and effectively cleanse the articles that are being laundered.

Further objects of my invention are to produce a clothes washing device of a dolly or pounder type that can be easily and cheaply produced and which may be mounted for manual operation upon the end of a handle or holder, or used in connection with a power driven washing machine, in which event, the dolly or pounder is mounted on the lower end of a vertical reciprocating member.

With the foregoing and other objects in view, my invention consists in certain new and novel features of construction and arrangement of parts which will be herein-after more fully described and claimed, and illustrated in the accompanying drawings, in which:

50 Figure 1 is a top plan view of a washing device of my improved construction.

Fig. 2 is a side elevational view of the device.

55 Fig. 3 is an enlarged vertical section taken approximately on the line 3—3 of Fig. 2.

Referring by numerals to the accompanying drawings, which illustrate a practical embodiment of my invention; 10 designates the main body portion of the device, the same being preferably in the form of a disk 60 and constructed of any desired material, preferably wood or metal, and the underside of said disk is cut away to form a relatively large recess 11.

Secured in any suitable manner to the lower portion of the outer face of the body 10 is the upper portion of an annular wall or flange 12 that extends downward a short distance below the underside of disk 10, and the lower edge of said annular wall or flange 70 is reinforced by the provision of a relatively heavy bead such as 13.

Formed through the center of the body 10 and leading upwardly from the recess 11 therein, is an aperture 14, and lying across the same is a section 15 of reticulated material, preferably, wire netting, and the edge of which is secured in any suitable manner to the underside of body 10 immediately adjacent to the opening therein. 80

Seated in the body 10 and disposed about the opening 14 therein, are upwardly projecting members such as pins or screws 16, and secured to the upper ends thereof and spaced a short distance above the top surface of the body 10, is a disk 17 that is provided with a centrally arranged socket 18 and which latter receives the lower end of a handle such as 19.

Formed through the disk 17 is a series 90 of apertures 20, and loosely arranged in the space between said disk and the body 10 is a disk 21, preferably of metal, the same being of sufficient size to entirely close the opening 14. This disk is free to move vertically through the space between disk 17 and the body 10, and it is held in position between said parts by the disk supporting pins or screws 16 and by a series of pins or screws 22 that are seated in member 10 and which 95 act as spacers and bearings for said disk.

In the operation of my improved washing device, handle 19 is manually engaged and the device is forced downwardly into engagement with articles that are being 105 laundered, and, as said device is moved downwardly through the water in which the articles are submerged, a portion of the water will flow upwardly through the centrally arranged opening, thereby forcing disk 21 110

upwardly against the underside of perforated disk 17, and when so positioned, said disk 21 will act as a deflector to cause the water to flow radially outward between the 5 edge of disk 17 and the outer upper edge of body 10, and the water thus forcibly delivered outward will be thrown directly against and through the immediately adjacent articles that are being laundered and 10 consequently producing cleansing effect thereupon.

On the upward movement of the device, water will flow rapidly through the openings 20 in disk 17, thereby forcing valve 15 disk 21 downwardly on to the top of body 10 to close opening 14, and as the device continues in its upward movement, a partial vacuum will be established in the recess or chamber 11 in the underside of body 20 10 and consequently producing suction upon the surrounding water and the articles that are being cleansed, and which suction draws the water through said articles with cleansing action.

25 In the event that my improved device is utilized in connection with power driven washing machines, a number of the devices may be arranged on the underside of a suitable support such as a spider and which latter is vertically reciprocated in any suitable manner.

The reticulated member 15 prevents articles that are being laundered from passing upwardly through opening 14 and interfering with the operation of valve disk 21 30 in the space between members 10 and 17.

A washing device of my improved construction is comparatively simple, may be easily and cheaply produced, and is very 40 effective in operation, due to its action alternately forcing and sucking the water through the articles that are being laundered.

Obviously, minor changes in the size, 45 form and construction of the various parts of my improved washing device may be made and substituted for those herein shown and described without departing from the spirit of my invention, the scope of which 50 is set forth in the appended claims.

I claim as my invention:

1. A washing device comprising a member provided with an opening, a perforated disk supported by and arranged above said 55 member, and a valve member loosely arranged between said member and said per-

forated disk, so that upward movement of said device would close said opening.

2. In a washing device, a member provided in its underside with a recess, there being an opening formed through said member and leading upwardly from said recess, a perforated disk arranged above and spaced apart from said recessed member, and a valve member loosely arranged in the space 65 between said recessed member and the perforated disk, which valve member is adapted to close the opening in said recessed member.

3. In a washing device, a member provided in its underside with a recess, there being an opening formed through said member and leading upwardly from said recess, a perforated disk arranged above and spaced apart from said recessed member, a valve 70 member loosely arranged in the space between said recessed member and the perforated disk, which valve member is adapted to close the opening in said recessed member, and a reticulated member lying across 75 the opening in said recessed member.

4. A washing device comprising a member provided with an opening, a perforated disk supported by and arranged above said member, a valve member loosely arranged between said member and said perforated disk, said valve adapted to close said opening and an operating handle connected to said perforated disk.

5. In a suction washing device, a member provided in its underside with a recess, there being an opening through said member, a disk carried by and spaced apart from said recessed member, and a valve member loosely arranged in the space between said recessed member and said disk, which valve is adapted to close the opening in said recessed member.

6. In a suction washing device, a member provided in its underside with a recess, there being an opening through said member, a disk carried by and spaced apart from said recessed member, a valve member loosely arranged in the space between said recessed member and said disk, which valve is adapted to close the opening in said recessed member, and a handle connected to said disk.

In testimony whereof I have signed my name to this specification.

MARTEN MANFRED.
